PRESS WITH EJECTOR RAM OPERATED
WITHOUT AUXILIARY PRESSURE SOURCEPaul C. Pocock, Marion, Ohio, assignor to The
Hydraulic Development Corp. Inc., Wilming-
ton, Del., a corporation of Delaware

Application June 7, 1938, Serial No. 212,327

10 Claims. (Cl. 100—71)

This invention relates to presses, and in particular, to arrangements for operating auxiliary rams in hydraulic presses.

One object of this invention is to provide a hydraulic press operating circuit having means for operating an auxiliary ram, such as an ejector ram, without the use of an auxiliary pressure source.

Another object is to provide a hydraulic press operating circuit, wherein an auxiliary ram is operated by fluid supplied to the push-back cylinders which retract the main ram.

Another object is to provide a hydraulic press operating circuit, wherein a single pump is arranged to provide pressure fluid not only for operating the main ram and push-back rams, but also an auxiliary ram, the latter being arranged so that it may be optionally made inoperative, and so that its speed of operation may be adjusted.

Another object is to provide a hydraulic press operating circuit, wherein an independent pressure-operated device, such as an auxiliary ram, is actuated by the pressure fluid supplied in response to the motion of one of the press plungers.

The drawing illustrates diagrammatically and in section a hydraulic press operating circuit actuating an auxiliary ram, such as an ejector ram, according to the present invention.

In general, the hydraulic press circuit of the present invention includes a main ram and push-back rams supplied with pressure fluid from a pump through a four-way valve. Hydraulically connected to the push-back rams is an auxiliary ram, such as an ejector ram, wherein the opposite sides of the ram head are of different areas and provide a differential effect according to which the speed of the ejector ram may be adjusted to the desired working conditions. Since both sides of the ejector ram are connected to both sides of the push-back rams, this differential effect is regulated by suitable valves placed in the circuit thereof.

Referring to the drawing in detail, the hydraulic press circuit shown herein comprising a main cylinder 10 containing the head 11 of a main plunger 12, the cylinder 10 being surmounted by a surge tank 13. The main plunger 12 is provided with arms 14, connected to the piston rods 15 of the push-back pistons 16, reciprocable within the push-back cylinders 17. The main cylinder 10 is provided with ports 18 and 19 at its opposite ends, communicating respectively with conduits 20 and 21 leading, respectively, to the

four-way valve 22 and to the surge tank 13. The conduit 21 is also connected by the conduit 23 to the discharge side of the four-way valve 22, so that the space beneath the main piston head 11 serves merely for the reception of slippage fluid, and does not provide a double-acting effect.

Leading from the surge tank 13 is the conduit 24 connected at its opposite end to the pump 25 on the suction side thereof. From the pressure side of the pump 25 the conduit 26 runs to the four-way valve 22. The remaining conduit 27 from the four-way valve 22 leads to the lower port 28 in the left-hand push-back cylinder 17. This is connected to a similar port in the right-hand push-back cylinder 17 by the cross conduit 29. The upper ends of the push-back cylinders 17 are provided with ports 30, interconnected by the cross conduit 31. From the latter the branch conduit 32 runs to the two-way valve 33, from 20 which the conduit 34 runs to the surge tank 13.

Arranged beneath the main plunger 12 is an ejector cylinder 35, having an ejector piston head 36 and ejector plunger 37 reciprocable therein. The cylinder 35 has ports 38 and 39 at the lower and upper ends thereof. From the lower port 38 the conduit 40 runs to the cross conduit 31, interconnecting the upper sides of the push-back cylinders 17. From the upper port 39 in the ejector cylinder 35, however, the conduit 41 runs to the cross conduit 29, beyond which the conduit 43 containing the manual valve 42 runs to selectively interconnect the cross conduits 29 and 31.

In the operation of the press circuit shown in the figure, to perform a pressing stroke the four-way valve 22 is shifted by means of its operating handle 44, so that the pump 25 discharges pressure fluid through the line 26, the valve 22, the conduit 20 and the port 18, into the space above the main piston head 11, causing the latter to move downwardly and carrying with it the push-back plungers 15 and their piston heads 16. Fluid displaced from the space beneath the piston head 16 escapes through the conduits 29 and 21, the valve 22, the conduits 23 and 21 to the surge tank 13. Any fluid which has escaped by slippage past the main piston head 11 will be forced by this same operation through the conduit 21 to the surge tank 13.

When the pressing operation has proceeded far enough, the handle 44 of the four-way valve 22 is shifted so that pressure from the pump 25 is admitted by way of the conduit 26, the valve 22 and the conduits 27 and 29 to the ports 28 in the push-back cylinders 17, beneath the push-back

piston heads 16. The valve 42 is assumed to be closed and the valve 33 open. Under these circumstances, the push-back pistons 16 will rise, carrying with them the main plunger 12 attached to the main piston head 11. The oil forced out of the space above the main piston head 11 is discharged through the port 18, the conduit 20, the four-way valve 22 and the conduits 23 and 24, into the surge tank 13.

Meanwhile, the fluid forced out of the space above the push-back piston heads 16 is forced through the ports 30, into the conduits 31, 32 and 40. Since the two-way valve 33 is assumed to be open, this fluid will be discharged directly into the surge tank 13 by way of the conduit 34. In order to perform an ejection stroke, however, the operator closes the two-way valve 33. The fluid forced out of the upper portions of the push-back cylinders 17 is therefore forced from the conduit 31, into the conduit 40, and through the port 38 of the ejector cylinder 35, into the space beneath the ejector piston head 36. This action causes the ejector plunger 37 to rise, thereby ejecting the workpiece from the dies, or other holding arrangement.

It will be observed that the return side of the ejector piston head 36 is connected through the conduits 41 and 29 to the lower ends of the push-back cylinders 17. Consequently, a differential effect is produced upon the push-back plungers 15, whereby the difference in area between the bottom of each push-back piston head 16 and the annular space above it provides the unbalanced force which moves the push-back plunger 15 upwardly. When the ejector has been raised to a sufficient height to eject the workpiece, the operator opens the two-way valve 33. When this occurs the pressure in the space above the ejector piston head 36 will return the latter to its lowermost or retracted position, because the space beneath the ejector piston head 36 is connected, through the conduits 40, 31, 32 and 34, and the valve 33 to the surge tank 13.

In the usual pressing procedure it is found desirable to eject the workpiece as slowly as possible without stopping or interrupting the press operating cycle. By the arrangement of the present invention the ejector plunger 37 may be made to operate as slowly as desired by properly proportioning the annular area above the ejector piston head 36 to the circular area beneath it. Ordinarily, the ejector possesses approximately one-half the stroke of the main ram, hence, a satisfactory design would be to make the ejector plunger 37 move at half the speed of the main ram. This would be done by properly apportioning the annular and circular areas of the piston head 36 in the manner described above, and would cause the ejector plunger 37 and the main plunger 12 to complete their strokes at the same time.

It will be understood by anyone skilled in the press art that many different kinds of dies can be employed in connection with the present invention, depending upon the nature of the workpiece to be made. Such dies are well known and their details form no part of the present invention. Merely for purposes of illustration, however, the applicant has shown a pair of cooperating dies 45 and 46 attached to the platen 12 and press bed 50, respectively. When these dies come together they convert the disc-shaped blank 48 into the cup-shaped workpiece indicated by the dotted lines 48^a. The die 46 is provided with a bore 49 for the passage of the ejec-

tor rod 37^a. The latter forms an extension of the ejector plunger 37 and ejects the workpiece 48^a from the die 46 when the ejector plunger 37 rises in the manner set forth above.

It will be understood that I desire to comprehend within my invention such modifications as come within the scope of the claims and the invention.

Having thus fully described my invention, what I claim as new and desire to secure by Letters Patent, is:

1. In a hydraulic press circuit, a main plunger, a push-back plunger operatively connected with said main plunger and adapted to effect the retraction stroke thereof, an ejector plunger operable during the retraction stroke of the main plunger by fluid expelled by said push-back plunger, a source of pressure fluid, means for selectively directing pressure fluid from said source to said main plunger or said push-back plunger, and a hydraulic circuit interconnecting said plungers.

2. In a hydraulic press circuit, a main plunger, a double acting push-back plunger operatively connected with said main plunger and adapted to effect the return stroke thereof, a double acting ejector plunger having fluid connections with both sides of said push-back plunger and being operable by fluid acted upon by said push-back plunger during the working stroke thereof, a fluid reservoir adapted to communicate with one side of said push-back plunger and said ejector plunger, a source of pressure fluid for supplying pressure fluid to the other side of said push-back plunger and said ejector plunger, means for selectively directing pressure fluid from said source to said main plunger or said push-back plunger, and a hydraulic circuit interconnecting said plungers.

3. In a hydraulic press circuit, a main plunger, a push-back plunger, an ejector plunger, a fluid reservoir, a source of pressure fluid, means for selectively directing pressure fluid from said source of pressure fluid to said main plunger or said push-back plunger, and a hydraulic circuit interconnecting said plungers for feeding fluid acted upon by said push-back plunger to said ejector plunger for operating the same, said push-back plunger and said ejector plunger being double-acting, the retraction side of said ejector plunger being hydraulically connected to the push-back side of said push-back plunger and the ejection side of said ejector plunger being hydraulically connected to the return side of said retraction plunger and to said fluid reservoir.

4. In a hydraulic press circuit, a main plunger, a double acting push-back plunger connected with said main plunger, a double acting ejector plunger, a source of pressure fluid, means for selectively directing pressure fluid from said source to one side of said main plunger or said push-back plunger, a fluid reservoir adapted to communicate with the other side of said main cylinder, and a hydraulic circuit interconnecting said plungers for feeding fluid acted upon by said push-back plunger to said ejector plunger for operating the same, the retraction side of said ejector plunger being hydraulically connected to the push-back side of said push-back plunger and the ejection side of said ejector plunger being hydraulically connected to the return side of said retraction plunger.

5. In a hydraulic press circuit, a main plunger, a double acting push-back plunger, a double acting ejector plunger, a fluid reservoir adapted to

communicate with one side of said push-back plunger and said ejector plunger, a source of pressure fluid for supplying pressure fluid to the other side of said push-back plunger and said ejector plunger, means for selectively directing pressure fluid to said main plunger or said push-back plunger, a hydraulic circuit interconnecting said plungers, the retraction side of said ejector plunger being hydraulically connected to the push-back side of said push-back plunger and the ejection side of said ejector plunger being hydraulically connected to the return side of said push-back plunger, and means for selectively interconnecting the opposite sides of said push-back plungers.

6. In a hydraulic press circuit, a main cylinder with a main plunger, a push-back cylinder with a push-back plunger, an ejector cylinder with an ejector plunger, a fluid reservoir adapted to communicate with said cylinders, a pump, means for delivering the pressure fluid from said pump to the push-back side of said push-back plunger, and means respectively connecting the ejection and return sides of said ejector plunger with the return and push-back sides of said push-back plungers for transferring fluid from said push-back cylinder to said ejector cylinder to operate said ejector plunger.

7. In a hydraulic press circuit, a main cylinder with a main plunger, a push-back cylinder with a push-back plunger, an ejector cylinder with an ejector plunger, a fluid reservoir adapted to communicate with said cylinders, a pump, means for delivering the pressure fluid from said pump to the push-back side of said push-back plunger, means respectively connecting the ejection and return sides of said ejector plunger with the return and push-back sides of said push-back plungers, and means selectively connecting said ejector cylinder with said fluid reservoir.

8. In a hydraulic press circuit, a main cylinder

with a main plunger, a push-back cylinder with a push-back plunger, an ejector cylinder with an ejector plunger, a fluid reservoir adapted to communicate with said cylinders, a pump, means for delivering the pressure fluid from said pump to the push-back side of said push-back plunger, means respectively connecting the ejection and return sides of said ejector plunger with the return and push-back sides of said push-back plunger, and means selectively connecting the ejection side of said ejector plunger with said fluid reservoir.

9. In a hydraulic press circuit, a main cylinder with a main plunger, a plurality of push-back cylinders, each with a push-back plunger, an ejector cylinder with an ejector plunger, a fluid reservoir adapted to communicate with said cylinders, a pump, means for delivering the pressure fluid from said pump to the push-back side of said push-back plunger, means respectively connecting the ejection and return sides of said ejector plunger with the return and push-back sides of said push-back plungers, and means for selectively interconnecting the push-back and return sides of said push-back plungers.

10. In a hydraulic press circuit, a main cylinder with a main plunger, a push-back cylinder with a push-back plunger, an ejector cylinder with an ejector plunger, a fluid reservoir adapted to communicate with said cylinders, a pump, means for delivering the pressure fluid from said pump to the push-back side of said push-back plunger, means respectively connecting the ejection and return sides of said ejector plunger with the return and push-back sides of said push-back plunger, means selectively connecting the ejection side of said ejector plunger with said fluid reservoir, and means for selectively interconnecting the push-back and return sides of said push-back plunger.

PAUL C. POCOCK.
